MARKING INSTRUMENT OR SCRIBER

Carl Bronner, Maplewood, N. J.

Application April 2, 1957, Serial No. 650,241

2 Claims. (Cl. 30—164.9)

This invention relates in general to a marking instrument or scribe for making lines or inscriptions on coated or uncoated surfaces, and more particularly, the invention is concerned with the marking of coated synthetic plastic compositions such as are frequently used in the making of price tags and identification tags for various articles such as pieces of jewelry.

It is difficult, if not impossible, to write with the most commonly known scribes, because either the scribing points merely dent the surface of material such as a sheet of plastic composition, or the scribing points stick or dig into the material during efforts to change the directions of movements of the points while the latter are in contact with the material, as would be the case in writing operations. Moreover, the scribing points of known scribes, particularly the conical metal points, quickly become dull, worn out or ineffective, and it is difficult, if at all possible, to make fine lines or shaded lines with known scribes.

Prime objects of the present invention are to provide a novel and improved scribe which shall overcome the above mentioned objections to and disadvantages of known scribes, and to provide such a scribe with which at the will of the user straight or curved lines such as are used in writing, can be easily produced, either in fine or shaded form.

Further objects of the invention are to provide a scribe of this character the scribing point of which shall have a plurality of angularly related surfaces that meet in sharp angles so that the point will actually cut a surface over which it is drawn as distinguished from merely indenting or scratching the surface; and to provide such a scribe which shall have in a scribe head a plurality of scribing points of the nature described that may be separately or individually brought into operation at the will of the user by a simple rotation of the scribe in the hand of the user.

Other objects of the invention are to provide a novel and improved combination of a scribe point of the character described and a holder or handle therefor, and to obtain other advantages and results that will be brought out by the following description in conjunction with the accompanying drawings in which—

Figure 1 is a composite side elevational view of the handle and point portion of the scribe and a removable cap therefor;

Figure 2 is a greatly enlarged composite side elevational view and central vertical sectional view through the scribing head portion of the scribe;

Figure 3 is a horizontal sectional view on the plane of the line 3—3 of Figure 2;

Figure 4 is a similar view on an enlarged scale on the plane of the line 4—4 of Figure 2;

Figure 5 is a fragmentary enlarged side elevational view of the scribe head;

Figure 6 is an end view thereof; and

Figure 7 is a fragmentary central vertical sectional view through the scribe head on the plane of the line 7—7

2

of Figure 6 but showing the head inverted and in marking position relative to a surface to be marked.

Specifically describing the illustrated embodiment of the invention, the reference character A designates the main or body portion of the handle or holder which may be formed of suitable material such as a plastic composition, and in one end of which is snugly fitted a tip B that serves as a firm mounting for the scribe shank C at one end of which is the scribe head D.

10 The invention contemplates a scribe point of novel construction and a scribe head having a plurality of such points any one of which can be used for marking and writing purposes.

As best shown in Figures 6 and 7 each writing point 15 comprises a plurality of angularly related surfaces that meet at a common sharp angle or corner. More particularly, describing the point, it will be seen that the four surfaces 1, 2, 3 and 4 meet at a common sharp angle or corner 5 and provide a plurality of angularly related cutting edges that meet to form the marking points.

The scribe head is conveniently formed by cutting a plurality of V-shaped longitudinal grooves 6 in the peripheral surface of a cylinder, the side walls of the grooves forming sharp-edged longitudinal ribs 7 parallel to the 25 longitudinal axis of the head that terminate at one end of the head, and said end of the head is provided with radial grooves 8 each of which constitutes a continuation of one of the grooves 6 and preferably gradually decreases in depth toward the center or axis of the cylindrical head.

Each scribe point 5 thus comprises a plurality of sharp angularly related edges so that no matter in which direction the point is moved over a surface E, one or more of the edges will cut into the surface and actually remove shavings of the material; and the point can be moved with equal ease or facility in any direction. Thus, the point can be used for making fine straight lines or fine curved lines such as are used in writing or the point can be used for making shaded lines, straight or curved, 40 by simply varying in the writing the pressure at which the scribe point is forced against the surface.

Preferably, the scribe head D will be formed of hard, cutting steel and conveniently may be made integral with the shank C. While the shank might be easily separably 45 mounted in the tip, the shank has been shown as formed with a tapered portion 9 inwardly of the head D that has a drive fit in a similarly tapered portion 10 of a bore 11 that extends coaxially through the tip B. Preferably, the head D is driven through a cylindrical portion 12 of said bore so as to cause an interlock between the wall of the tip and the ribs and grooves of the head as best shown in Figure 4, thereby positively preventing rotation of the scribe head in the tip and at the same time providing a firm support for the scribe head during marking operations.

It will thus be seen that each marking point 5 is formed by a plurality of angularly related surfaces 1, 2, 3 and 4, the surfaces 3 and 4 being parallel to the longitudinal axis of the head D and providing a rib or ridge that is V-shaped in cross section, and the surfaces 1 and 2 being at angles to said axis of the head and meeting each other to form a V-shaped ridge that is radially disposed to said axis and meets one of the ribs formed by the surfaces 3 and 4, at one end, of the head. It will also be observed that there are a plurality of marking points 5 spaced around the axis of the head and disposed in radial relation thereto in a common plane that is perpendicular to said axis, and that the points can be brought individually into operation by simple rotation of the scribe in the user's hand, and always at least one point will be in position for use. The angle of meeting of the ridges

at the marking point 5 is not critical but is preferably 90° as best shown in Figure 7.

While it is not at all necessary, a cap F may be separably fitted on the end of the main portion A to normally cover the scribe head D.

While I have shown and described the now preferred embodiment of the invention, many modifications and changes can be made in the construction of the scribe and holder and in the specific construction of the scribe head and scribe points, all within the spirit and scope of the invention.

What I claim is:

1. A scribe comprising a head having a longitudinal axis, a plurality of angularly related surfaces extending along said axis that meet in cutting edges, and a plurality of angularly related surfaces on the end of said head at angles to said axis that meet in cutting edges, each of the second-mentioned surfaces meeting one of the first-mentioned surfaces in a sharp cutting edge, said edges meeting in a common marking point, so as to provide a plurality of said marking points radially disposed with respect to said axis and equidistantly spaced from said

axis in a plane perpendicular to said axis, a shank projecting from one end of said head, and a holder having a bore therethrough a portion of which has cylindrical walls and in which said head is drive-fitted with the 5 first-mentioned cutting edges interlocked with said walls thereof.

2. A scribe as defined in claim 1 wherein said shank has a tapered portion and said bore in the holder has a portion whose walls are correspondingly tapered and into which the tapered portion of the shank is drive fitted with said head projecting from the end of the holder.
